(57) **CLAIM**

The ornamental design for a therapeutic cooling device, as shown and described.

DESCRIPTION

FIG. 1 is a top perspective view of a therapeutic cooling device showing my new design;

FIG. 2 is another top perspective view thereof;

FIG. 3 is a front elevational view thereof;

FIG. 4 is a rear elevational view thereof;

FIG. 5 is a side elevational view thereof, both the left and right sides being identical; and,

FIG. 6 is a top elevational view thereof, the bottom thereof which is not shown, being devoid of ornamentality.

The broken lines shown in the FIGS. 1-6 are for illustrative purposes only and form no part of the claimed design.

1 Claim, 5 Drawing Sheets
